SHIPPING CONTAINER

Roy G. Churan, Oak Lawn, Ill., assignor to Growth International Industries Corp., Peotone, Ill., a corporation of Delaware

Filed Mar. 11, 1968, Ser. No. 10,909

Term of patent 14 years

Int. Cl. D9—07

U.S. Cl. D9—216

FIG. 1 is a front elevational view of a shipping container showing my new design, the rear being substantially the same in appearance;

FIG. 2 is an elevational view looking from the right of FIG. 1, the opposite side being substantially the same in appearance;

FIG. 3 is a top plan view;

FIG. 4 is a bottom plan view thereof;

FIG. 5 is a sectional view taken substantially along line 5—5 in FIG. 1; and

FIG. 6 is a sectional view taken substantially along line 6—6 in FIG. 2.

I claim:

The ornamental design for a shipping container, substantially as shown and described.
